Maynard French - Albany New York
Letters Patent Dated March 3 1836

The schedule referred to in those Letters Patent and making part of the same containing a description in the words of the said Maynard French himself of his improvement in the Caps or Caps for Rolling Stones.

To all to whom these presents shall come. Be it known that I, Maynard French of the City and County of Albany in the State of New York have invented a new and useful improvement in the construction and adaptation to use of an elevated Cap, to be applied to said furnaces, and that the following is a full and accurate description and specification thereof. The improvements and invention claimed by the said Maynard French, consists - First, in the elevation of the crown or top of the cap, from its bearing stones, of about three inches and one half, for an ordinary size stone. This elevation however is to be increased or diminished according to the various sizes of stones to which the cap may be applied. Second, in the construction and arrangement of the partitions, adopted to the number, shape and size of Boilers and other implements used in the stove. These partitions may be either circular, angular, square, parallelogram or any other convenient, useful or desirable shape or form.

When the partitions are circular, they extend close to the upper part of the stove, with semicircular, or other shaped openings on the outer edge of all the partitions to permit the smoke and air to pass from one chamber to another, which are formed in the partitions, freely, around and under the bottoms of Boilers and other implements used in the cap of the

The elevation may be suspended, inclining to, circular. The construction may be made of any convenient or desired width and may be plain or constructed with a wheel purpose of being moved by a pinion. This cap

be moved by a hand, lever or rack and pinion, and upon a plane bearing or upon rollers, thereby giving to it a circular or rotary motion on the top of the stove, to which it may be applied. The sleeve or cap may be constructed with an increased or diminished number of openings, and it is in all instances to be adapted to the particular use or business to which it is to be applied. The cap is to be made of cast or any kind of malleable metal, Iron Copper and brass are the best. This cap and all the variously constructed ones, on the principles herein described, may be adapted and applied to the kind and description of stoves as are described Specified and particularized. In every Stove in Elisha Town, both of the State of Vermont or a common stationary or moveable stove or furnace, either of clay or metal; and the heat may be communicated to the boilers and other implements in the said stove, either from the stove or furnace to which the said cap is applied or from any other stove or furnace. And the said Maynard French distinctly claims his invention and improvement, the elevation of the cap, or caps, the formation of the Chambers, by the various partitions on the underside of the cap or caps, the method of conveying the smoke and heat from chamber to chamber and the adaptation and application of the said caps to stoves and furnaces as aforesaid.
